UNITED STATES PATENT OFFICE.

BENSON P. COOPER AND ISAAC COHEN, OF PHILADELPHIA, PENNSYLVANIA.

DESIGN FOR AN ORNAMENTAL STAND.

SPECIFICATION forming part of Design No. 15,423, dated September 23, 1884.

Application filed July 26, 1884. Term of patent 7 years.

To all whom it may concern:

Be it known that we, BENSON P. COOPER and ISAAC COHEN, both citizens of the United States, residing in the city and county of Philadelphia, State of Pennsylvania, have invented and produced a new and original Design for a Stand, of which the following is a specification, reference being had to the accompanying drawing, forming part thereof.

10 The leading feature of our design is the body of the stand of the form of a distended fan, and blocks on the face thereof.

15 A represents the body of the stand, the same being of the form of a distended fan, and B represents a leg or prop, presenting together

an easel-like appearance. On the face of the body are blocks C, which are radially arranged, thus rendering the design interesting and attractive.

We claim—

20 The design for an ornamental stand having a body, A, of the form of a distended fan, with blocks C on the face thereof, as above described and shown.

BENSON P. COOPER.
ISAAC COHEN.
